UNITED STATES PATENT OFFICE.

EDGAR C. SIDDENS, OF SHATTUCK, OKLAHOMA.

KITCHEN-INDICATOR.

1,220,696.

Specification of Letters Patent. Patented Mar. 27, 1917.

Application filed February 16, 1916. Serial No. 78,683.

To all whom it may concern:

Be it known that I, EDGAR C. SIDDENS, a citizen of the United States, residing at Shattuck, in the county of Ellis and State 5 of Oklahoma, have invented certain new and useful Improvements in Kitchen-Indicators, of which the following is a specification, reference being had to the accompanying drawings.

10 This invention relates to a kitchen indicator and has for its primary object to provide a very convenient and serviceable device whereby culinary wants of the housewife may be made known to the merchant or 15 delivery clerk.

It is another object of the invention to provide a device of the above character including a suitable baseboard having the names of various commodities printed in orderly arrangement upon its surface and a 20 compartment opposite each of the commodities in which the advertisement and name of the producer may be printed.

It is an additional object of the invention 25 to provide means for indicating the commodity of which a supply is desired, said means including wires arranged in grooves provided in the side and top edges of the baseboard, means for detachably connecting the wires together and mounting the same in said grooves, and buttons strung upon the wires and movable in notches or recesses provided in the edges of the baseboard.

30 35 With the above and other objects in view, my invention consists in the novel features of construction, combination and arrangement of parts to be hereinafter more fully described, claimed and illustrated in the accompanying drawing, in which,

Figure 1 is a front elevation of an indicator constructed in accordance with the preferred embodiment of my invention;

Fig. 2 is an edge view of the device; and 40 Fig. 3 is a section taken on the line 3—3 of Fig. 2.

Referring in detail to the drawing, 5 designates the body or base of the indicator which may be in the form of a heavy card- 50 board sheet, a thin wooden slab, or the same may be constructed of any desired composi-

tion material. Each of the vertical side edges and the top edge of this baseboard are provided with a longitudinally extending groove or channel indicated at 6, and spaced 55 notches 7 are cut into these edges of the baseboard, said notches traversing or intersecting the longitudinal grooves.

The surface of the board is marked off by a number of vertical lines into main divisions, said vertical lines extending from the horizontal line 8 in spaced relation to the top edge of the board to a point in spaced relation to the bottom edge of the board. Equidistantly spaced horizontal lines intersect the spaced vertical division lines and extend from one vertical edge of the board to the other. In this manner, the surface of the board is provided with a series of subdivided vertical columns. In the sub-divisions of the columns 9 and 10 at the opposite vertical edges of the board, the names of various household commodities are printed, while in the sub-divisions of the vertical columns 11 and 12 next adjacent to the respective columns 9 and 10, the particular trademarks of the respective commodities or the names of the manufacturers, are printed. The space between the horizontal line 8 and the upper edge of the board is also subdivided by spaced parallel vertical lines, and in each of these sub-divisions the names of fruits or vegetables are printed which are not manufactured and marketed under any particular trademark. 75 80 85

In the grooves 6 in the side and top edges of the baseboard, the wires 13 are adapted to be arranged. The ends of the top wire are angularly bent to extend into the side grooves 6 and are provided with eyes 14 to 90 which hooks 15 on the upper ends of the side wires are detachably connected. The lower ends of the side wires are also angularly bent, as at 16, and are adapted to be engaged in sockets provided in the baseboard 95 which communicate with the grooves 6. At intervals along the vertical edges of the board, the pins 17 are adapted to be removably engaged through openings in the board and across the grooves 6, outwardly of the 100 wires 13 arranged in said grooves. Thus the wires will be securely held in place.

Upon each of the wires, a series of spaced buttons 18 are pivotally engaged, the shanks of said buttons being movable in the respective notches 7 in the edges of the board. One 5 of these buttons is provided for each of the commodities indicated on the surface of the board.

From the foregoing description, taken in connection with the accompanying drawing, 10 the construction, manner of use, and several advantages of the device will be apparent. When the housewife desires to obtain a new supply of any one of the several commodities indicated on the surface of the board, 15 the particular button 18 opposite such commodity is moved upon the wire 13 and said button disposed over the surface of the board. Thus, the delivery boy may readily ascertain the desires of the housewife without 20 calling her from other duties with which she may be engaged. It is apparent that, if desired, the spaces to receive the names of additional commodities may be marked off on the surface of the board and the wires 25 13 removed and extra buttons strung thereon, said wires being then replaced in the edges of the board in the manner above explained. By providing the detachably connected series of wires removably mounted in the 30 edges of the board, additional buttons may be applied to the wires from time to time as the names of other commodities are added to the columns 11. Also, should any one of the buttons become broken or the shanks 35 bent so that they could not be properly operated, new buttons may be readily supplied. It will thus be seen that I have produced a very serviceable and convenient, though exceedingly simple indicator which 40 serves as an aid or reminder to the housewife, and as the several buttons may be arranged in their indicative positions as the need for replenishment arises, liability of failure to order such commodities through 45 forgetfulness will be obviated.

While I have shown and described the preferred construction and arrangement of the several parts of the device, it is to be understood that the invention is susceptible of considerable modification therein and I, therefore, reserve the privilege of adopting all such legitimate changes as may be fairly embodied within the spirit and scope of the invention as claimed.

Having thus fully described my invention, what I desire to claim and secure by Letters Patent is:—

1. An indicator of the character described including a board having various commodities indicated on the surface thereof adjacent to its edges, each of said edges having a longitudinal groove therein, wires engaged in said grooves, individually movable elements engaged upon the wires in spaced 60 relation to each other and movable to posi-

tions upon the surface of the board in juxtaposition to the respective commodities indicated thereon, and removable pins engaged in the board and transversing said grooves to removably retain the wires therein. 70

2. An indicator of the character described including a body board having various commodities indicated on the surface thereof adjacent to its edges, wires extending along the edges of the board and detachably connected to each other, individually movable elements engaged upon said wires in spaced relation and movable to positions upon the surface of the board in juxtaposition to the respective commodities indicated thereon, 75 and removable pins adapted to be engaged in the board in coöperative relation to the wires to detachably retain said wires in position. 80

3. An indicator of the character described including a bodyboard having commodities indicated upon the surface thereof adjacent to its side and top edges, wires disposed along the side and top edges of the board and detachably connected to each other, 85 spaced indicating members strung upon said wires and adapted to be moved to positions upon the surface of the board contiguous to the respective commodities indicated thereon, and means for detachably holding said 90 wires in place upon the edges of the board. 95

4. An indicator of the character described including a bodyboard having commodities indicated upon the surface thereof adjacent to its side and top edges, wires disposed along the side and top edges of the board and detachably connected to each other, 100 spaced indicating members strung upon said wires and adapted to be moved to positions upon the surface of the board contiguous to the respective commodities indicated thereon, and means removably mounted in the board to coöperatively engage with the wires on the side edges of the board and retain the 105 wires in their applied positions. 110

5. An indicator of the character described including a bodyboard having the names of commodities printed thereon along its opposite vertical edges and along its top edge, said board being provided in each of said edges 115 with a longitudinally extending groove and notches intersecting the grooves, a wire engaged in each of said grooves, the side wires being detachably connected to the ends of the top wire, a series of buttons strung 120 upon each of said grooves and having shanks movable in the respective notches whereby the buttons may be disposed upon the surface of the board contiguous to the respective commodities indicated thereon, and means for detachably holding the wires in place within the grooves in the board. 125

6. An indicator of the character described including a rectangular base having its longitudinal edges and one of its end edges 130

grooved, wires seated in said grooves, the terminals of the wire engaged in the end groove being angularly bent to extend into the side grooves and provided with hooks, 5 the side wires also having terminal hooks for detachable engagement with the respective hooks on the end wire, means co-acting with the side wires to removably hold the same in the grooves, and a plurality of in-

dicating elements movable upon each of said 10 wires with respect to the surface of the base.

In testimony whereof I hereunto affix my signature in the presence of two witnesses.

EDGAR C. SIDDENS.
